Structural member for supporting display media, such as signs and the like, in spaced relationship thereto, comprising an elongated channel member having longitudinal flanges, at least one elongated spacing member secured to the longitudinal flanges, and a pair of elongated attaching elements secured to the longitudinal flanges, each of which has a hole for a bolt, and a sign or other object secured to the attaching elements.

1. A structural member for supporting display media, such as signs and the like, in spaced relationship thereto, comprising an elongated channel member having longitudinal flanges, at least one elongated spacing member secured to the longitudinal flanges, and a pair of elongated attaching elements secured to the longitudinal flanges, each of which has a hole for a bolt, and a sign or other object secured to the attaching elements.

UNITED STATES PATENT OFFICE

1,986,721

STRUCTURAL MEMBER

Albert W. Froude, Ridgewood, N. J., assignor to
The American Steel and Wire Company of New
Jersey, a corporation of New Jersey

Application May 24, 1933, Serial No. 672,720

5 Claims. (Cl. 40—145)

This invention relates to structural members, and more particularly to U-shaped posts, which may be adapted to support display media, such as signs and the like.

5 One object of the invention is to provide a novel structural member enabling the attachment thereto of a substantial object in a firm and secure manner.

Another object is to provide means enabling 10 the attachment of signs, etc., to U-shaped posts without "buckling" or "dishing-in" of the sign.

Still another object is to provide novel means 15 for firmly securing reflector signs, or similar devices which require rearward projections, to conventional structural members, and in spaced relationship with respect thereto.

These and further objects will appear after referring to the drawing, in which:

20 Figure 1 is a front elevation of the device of the invention.

Figure 2 is a side elevation thereof.

Figure 3 is an enlarged fragmentary detail of Figure 2.

Figure 4 is an end elevation of a modified form 25 of the invention.

Figure 5 is an enlarged fragmentary detail of Figure 4.

Figure 6 is a view similar to Figure 5 but disclosing a further modification.

30 Figure 7 is a top plan of Figures 4 and 5.

Referring more particularly to the drawing, the numeral 2 designates a conventional U-shaped post or structural member provided with flanges 2^a.

35 According to the present invention, a pair of elongated attaching elements 3, which comprise U-shaped members provided with flanges 3^a, are disposed in contact with and transversely of the flanges 2^a of the U-shaped post 2, and welded as

40 at 4. The attaching elements 3 are provided with holes 3^b in order to facilitate the attachment of a sign generally indicated at 5, as by means of the bolts and nuts 6 and 6^a, respectively, providing for maintaining a reflector device

45 5^a, or other rearward projection, in spaced relationship from the post 2.

Referring to the modification disclosed in Figures 4 and 5, Z-shaped, or double-angled, attaching and spacing members 7 are provided in lieu 50 of the U-shaped members 3 and are similarly welded to the flanges 2^a of the post, as at 4, the bolt hole being indicated at 7^b.

Referring to Figure 6, a further modification is disclosed providing an attaching and spacing angle member 8, which is likewise secured to the

flanges 2^a of the post as by means of the welds 4, the hole for the bolt 6 being provided at 8^b. In each instance the attaching and spacing members provide a wide and elongated area for contact with the sign 5, or other object to be supported.

While I have shown and described several specific embodiments of my invention, it will be understood that I do not wish to be limited exactly thereto, since various modifications may 10 be made without departing from the scope of my invention, as defined in the following claims.

I claim:

1. A structural member for supporting display media comprising, in combination, an elongated 15 channel member of U-shaped cross-section having longitudinal flanges, elongated spacing members secured to the flanges of said channel member, and means associated with said spacing members for enabling attachment of said display 20 media.

2. A structural member for supporting display media comprising, in combination, an elongated channel member of U-shaped cross-section having longitudinal flanges, at least one elongated spacing member for bridging the longitudinal flanges of said channel member, said elongated spacing member being secured to said longitudinal flanges, and means associated with said spacing member 25 for supporting said display media in spaced relationship with respect to the longitudinal flanges of said channel member.

3. A structural member for supporting display media comprising, in combination, an elongated 35 channel member of U-shaped cross-section having longitudinal flanges, at least one U-shaped bridging plate provided with flanged portions which are secured to the longitudinal flanges of said channel member and in transverse relationship with respect thereto, and means associated with 40 said bridging plate at a point remote from its flanged portions for attaching said display media in spaced relationship with respect to said elongated channel member.

4. A structural member for supporting display media comprising, in combination, an elongated channel member of U-shaped cross-section having longitudinal flanges, at least one elongated double-angled member secured to the longitudinal flanges of said channel member and in transverse relationship with respect thereto, and means associated with the remainder of said double-angled member for supporting said display media in spaced relationship with respect to said elongated 45 channel member.

5. A structural member for supporting display media comprising, in combination, an elongated channel member of U-shaped cross-section having longitudinal flanges, at least one angle member having the end of one of its flanges secured to the longitudinal flanges of said channel mem-

ber and in transverse relationship with respect thereto, and means associated with the other of the flanges of said angle member for supporting said display media in spaced relationship with respect to said elongated channel member. 5

ALBERT W. FROUDE.
